UNITED STATES PATENT OFFICE

LEW KOEN, OF WILKES-BARRE, PENNSYLVANIA

INTERCHANGEABLE HANDLE

Application filed December 15, 1927. Serial No. 240,234.

The subject matter of this application relates to handles adapted to be quickly attached to or detached from tools or other implements which are commonly supplied with fixed handles.

5 The main object of the invention is to provide a handle having a central body made of wood and shaped conveniently to fit the average hand and having metallic parts 10 which can be used repeatedly with similar wooden bodies, which, as is well known, are frequently broken and require replacement.

Another object of the invention is to form the handle with wear resisting metallic 15 sockets and securing members which are practically unbreakable, and to which the cheap wooden handle bodies are adapted to be very quickly secured whenever it becomes necessary to replace a broken wooden handle.

20 A further object of the invention is to provide a set of interchangeable socket members, adapted to be secured to and form part of the handle, which add greatly to the utility of the handle and adapt it for uses 25 in many peculiar situations and in many parts.

Other objects of the invention will become apparent as the detailed description proceeds.

30 In the drawings:—

Figure 1 is an elevation of a hammer, with parts thereof in section, having a detachable handle applied thereto;

Figure 1^a is a section on the line 1—1 of 35 Figure 1;

Figure 2 is a fragmentary sectional elevation of the handle as applied to a hack saw;

Figure 3 is a sectional elevation of the 40 handle as applied to a soldering iron;

Figure 4 is a vertical transverse section on the line 4—4 of Figure 3;

Figure 5 is a sectional elevation showing the handle as applied to a trowel or similar 45 tool;

Figure 6 is a longitudinal section of the handle provided with a 90 degree socket member;

Figure 7 is an end elevation of the parts 50 shown in Figure 6;

Figre 8 is a modified form of the invention having a socket formed at each end to receive the corresponding plugs of tools or other implements;

Figure 9 is a longitudinal section of a 55 screw-driver embodying this invention;

Figure 10 is a section on the line 10—10 of Figure 9;

Figure 11 is fragmentary section of a 60 handle embodying this invention and applied to a part of an adjustable wrench having a stub handle formed as a plug adapted to seat in the socket of my handle;

Figure 12 is an elevation illustrating the 65 combined use of the handle shown in Figures 1 and 8 and the different types of sockets disclosed herein; and,

Figure 13 is a similar elevation illustrating the parts of Figure 12 in a different assembled relation to each other.

As is well known, the wooden handles of hammers and similar tools are frequently broken in use and their replacement is usually a troublesome job. To obviate this, I have provided a hammer head 1 with a steel rod 2, having a tapered end 3 adapted to fit in a correspondingly tapered socket 4 in the hammer head 1. The tapered end 3 projects beyond the head 1 and has an aperture 5 extending therethrough to receive a cotter or other lock pin 6 for locking the head 1 securely to the rod 2.

The rod 2 is preferably polygonal in cross section and has its free end adapted to fit snugly into the socket 7 of a socket member 8.

The end of rod 2 entering socket 7 constitutes a plug 7' for the socket and is provided in one face thereof with a yieldingly mounted ball 9 adapted to be forced by spring 10 into a corresponding recess 11 in the rod 2. This ball and recess construction provides for quick assembling of the connecting parts, and may be supplemented by a set screw 12 screw-threaded into the socket member 8 and having a point 13 adapted to engage the rod 2 and lock it securely in member 8.

The outer end of socket member 8 is tapered to form a frusto conical or pyramidal plug 14 adapted to seat in a corresponding socket 15 formed in one end of a wooden handle 16.

To lock the handle 16 securely to the member 8, the handle is axially bored to receive a hollow bolt 17 having one end 18 thereof screwthreaded or otherwise rigidly connected to the socket member 8.

The other end of handle 16 is provided with a counter bore 18' into which the other screw threaded end 19 of bolt 17 projects; and a pair of nuts 20 and 21 are threaded on 10 to this end 19 to lock the handle 16 secured to the bolt 17 and socket member 8. The central bore 22 may be used to hold a brad awl 23 or similar tool, having a T head adapted to turn it or shaped to rotate the nuts 20 and 15 21.

The handle constructions of Figures 2, 3, 5, 6 and 11 are identical with that shown in Figure 1 and the corresponding parts thereof are similarly numbered.

Figure 2 shows a hack saw frame 24 provided with a saw controlling plug 25 detachably secured to a handle 16.

Figure 3 illustrates the invention as applied to a soldering iron 26 which has the end 25 of its rod 27 shaped to form a plug fitting the socket 8. The bore 22 in this case may be used as a conduit for electric wires 28 and 29 which may be fixed to the plug end of the rod 27. An insulating cap 30 may be fixed 30 in any suitable manner to the end of handle 16 if desired.

In Figure 5 the handle 16 is shown as detachably secured to a 90 degree elbow plug 31 which is integrally or otherwise secured to 35 a trowel or other blade 32.

Figures 6 and 7 show a handle member 16 secured to 90 degree socket member 33 having its socket 34, identical in shape with socket 7, adapted to receive the corresponding plug 40 end 35 of a rod 36 which may be a mere extension rod, or which may form a handle of any kind.

In Figure 8 a handle member 37 is axially bored to receive a hollow bolt 38; similar 45 to the bolt 17 and having a socket member 8 secured to receive the corresponding plug end of rods 39 or 40.

In the screw driver shown in Figure 9, the handle 16 provided at one end with a 50 metal ferrule or cap 41; and at its other end is secured to a long socket member 42 in which a screwdriver blade 43 may be reversibly secured. In this case the inner end of the screw driver is provided with a gimlet or brad awl 44 which may be brought into use by reversing the screwdriver in the socket.

Figure 11 illustrates the handle as applied to an adjustable wrench 45, which has its end 60 46 formed as a plug to fit the socket members 8 or 33.

Figures 12 and 13 illustrate the various combinations which can be made up with the handles shown in Figures 1 and 8, the 65 straight and 90 degree socket members, and

suitable rods 47 formed at each end to fit and be secured to the sockets of members 8 and 33.

While I have described the handle as made of wood, it must not be considered as limited to manufacture of this material, since it may be made of ebonite, hard rubber or any other suitable material adapted to fit and protect the hand of the user of the tools.

I claim:

1. In a convertible socket wrench, an intermediate sleeve having ninety degree sockets detachably secured to each end thereof, a handle having a ninety degree socket at one end thereof, a rod seated in the last named socket and in one of said sockets, and a fourth socket detachably secured to the other of said sockets.

2. A wrench comprising three sleeves having wrench sockets detachably secured to each end thereof, and connecting rods detachably connected to the sockets at both ends of one of said sleeves and to a socket at one end of each of the remaining sleeves to form an assembled brace wrench.

In testimony whereof I affix my signature.

LEW KOEN.
